UNITED STATES PATENT OFFICE.

JOHN F. SHERLOCK, OF NEW YORK, N. Y.

ENVELOPE FOLDER.

1,413,689.

Specification of Letters Patent. Patented Apr. 25, 1922.

Application filed May 20, 1918. Serial No. 235,712.

To all whom it may concern:

Be it known that I, JOHN F. SHERLOCK, residing at New York, in the county and State of New York, have invented certain new and useful Improvements in Envelope Folders, of which the following is a specification.

This invention relates to an improved envelope folder, and one of the objects of the invention is to provide a new and improved device of the above character which may be manufactured cheaply, with the employment of a minimum amount of material which may be conveniently sent through the mail.

Another object of the invention is to provide an envelope folder of the above type comprising integrally formed sheet upon which the printing of the name of the addressee may be positioned on one side of the sheet so that when the sheet is folded the printed matter will be on the inside and concealed and the name of the addressee will be visible from the outside.

Another object of the invention is to provide a device of the above character which, when folded, may be opened in such a way that the part remaining closely simulates an ordinary billhead or the like.

Other objects and aims of the invention more or less specific than those above referred to, will be in part obvious and in part pointed out in the course of the following description of the elements, combinations, arrangements of parts and applications of principles, constituting the invention, and the scope of protection contemplated will be indicated in the appended claim.

Referring now to the drawings wherein I have illustrated preferred forms of embodiments of my invention,

Figure 1 is a plan view of a blank shaped to form one embodiment of my invention.

Figure 2 is a view in perspective showing the blank parts of the folder.

Figure 3 is a similar view showing the same in a further folded condition.

Figure 4 is a similar view showing the device folded and ready for the final closing operation.

Figure 5 is a plan view of the completed device.

Figure 6 is an elevational view of a blank shaped to form another embodiment of my invention.

Figure 7 is a view in perspective showing the same partially folded.

Figure 8 is a similar view showing the blank folded ready to receive the final closing operation.

Figure 9 is a plan view of the completed device.

Referring now to the drawings, wherein similar reference characters refer to similar parts throughout the several views thereof, the reference numeral 1 denotes generally the main portion of the blank which comprises the substantially rectangular parts 2, 3 and 4, and attached to the part 4 is an end flap 5. The parts 3 and 4 and the end flap 5 are provided upon one side with a flap 6, the length of said flap being co-incident with the combined width of the flaps of the parts 3 and 4 and the flap 5. The part 4 is also provided with a flap 7 upon the opposite end thereof from the flap 6. The part 3 is provided near its upper right hand corner with an elongated opening 8, and said flap is also provided with a cutaway portion 9 near its lower right hand corner. The parts 2, 3, 4 and the flap 5 are preferably provided with the scored lines 10 and 11, the purpose of which will be apparent hereinafter.

In forming the envelope folder from the blank, the construction of which has just been described, the flap 6 is first folded over as indicated in Figure 2 of the drawings and the flap 5 is thereupon folded as also indicated in this figure. The part 2 upon which the name and address of the addressee has been written at the point indicated at 12 in the drawings, is thereupon folded over as indicated in Figure 3 of the drawings, along the line 13 and the device is then folded upon the line 14 whereby the same will take on the appearance of Figure 4 of the drawings in which it will be noted that the name of the addressee will appear through the opening 8 which has been formed in the part 3. The entire device may then be closed by inserting the flap 7 in the space indicated at 15 which occurs between the faces of the parts 2 and 3 so that when the stamp indicated at 16 is placed upon the envelope, it will be engaged by the back face of the part 3 and the back face of the flap 7, whereupon that end of the envelope will be closed by said stamp. Inasmuch as the opposite end of the envelope is not permanently closed, it will be readily

seen that if the postal authorities desire to inspect the printed matter upon the inside of the envelope it may be readily opened by partially unfolding the flap portions occurring at that end of the device.

The flap 7, if desired, may also be scored as at 17 so that when the same is positioned within the envelope as above indicated, said scoring will lie directly in line with the scoring 11 upon the parts 2, 3 and 4 and the flap 5.

The addressee can open the envelope in the usual way, or, if desired, both ends thereof can be torn off along the scored lines 10 and 11, whereby the substantially rectangular sheet will be provided.

Referring now to the embodiment of my invention illustrated in Figures 6 to 9 inclusive, the same comprise a rectangular blank indicated generally at 18, which is divided into four substantially rectangular parts 19, 20, 21 and 22. The parts 21 and 22 are provided with a flap 23, said flap extending entirely along the lower edge of the flap 21 and a portion only of the lower edge of the part 22. The flap 20 is provided with a flap 24 upon its upper edge and the flap 22 is provided with a flap 25 upon its right hand edge. The part 20 is also provided with a longitudinal slot 26 in its upper right hand corner and with a cutaway portion 27 adjacent its lower right hand corner.

In folding the device from the blank just described, the same is folded along the line 28 and the flap 24 so that the part indicated at 29 thereof designed to carry the name and address of the addressee, will come opposite the opening 26. A flap 23 is then folded over as indicated in Figure 7 of the drawings, and in folding this flap it will be noted, forms a pocket 30 designed to receive the upper left hand corner 31 of the partially folded device, the insertion of this corner portion in the said pocket operating to locate the parts comprising that end of the device in closing position.

The device is now ready to be closed, which is effected by folding the flap 25 along the line 32 and inserting the same in the space provided directly underneath the cutaway portion of the part 27. The positioning of the stamp indicated at 33 will fasten the back of the part 20 to the back of the part 25, thus closing that end of the device. The scored lines such as indicated at 34 and 35 may be provided so that when

the device is closed the scored lines 34 and 35 and a scored line 36 provided upon the flap 25 will lie in engagement. Thereupon, the recipient of the envelope can open the same by merely tearing the same along these registering scored lines, and the same can be opened in the usual way by breaking the seal provided by the stamp.

It will accordingly be seen that I have provided a device well adapted to attain, among others, all the ends and objects above pointed out, in an extremely simple and efficient manner. As will be observed from the structure above described, while the same is self-contained, either embodiment may be readily utilized as the carrier for another piece of mail matter which may be inserted between the enclosures formed by the flap portions of the blank. The openings 8 and 26 provided in the blank may also be closed by transparent material such as oiled or waxed paper, if desired.

I claim—

An envelope folder, comprising a main sheet portion having the same width throughout and greater in length than in width, lines of perforations running lengthwise at equal distances from the side edges of the said main portion, an end flap greater in length than the width of the sheet, a side flap less in length than the length of the said main sheet portion and formed integrally with the said end flap, an inserting flap closure having a line of perforations arranged to coincide with one of said perforated lines of the sheet when the closure flap is inserted, the said closure flap being located upon the opposite side of the sheet from the said side flap and having a narrow tapering end located adjacent to the said end flap, the said closure flap growing wider as it extends from the end flap, and a cut-away edge portion located near the wide end of said closure flap whereby when said parts have been folded in as described the said cut-away portion lies directly over the widest part of the closure flap enabling the same to be easily reached and withdrawn.

In testimony whereof I affix my signature in the presence of two witnesses.

JOHN F. SHERLOCK.
